BLACKBOARD ERASER

Filed Aug. 9, 1930

INVENTOR

BY ATTORNEY ANTHONY A. ELNETT

Gustav Drews

UNITED STATES PATENT OFFICE

ANTHONY A. ELNETT, OF NEW YORK, N. Y.

BLACKBOARD ERASER

Application filed August 9, 1930. Serial No. 474,244.

This invention relates to black board erasers in general and more especially to erasers for black boards composed of slate or the like.

With black boards composed of slate such as extensively used in the schools of the United States today with which white crayons composed of chalk are used as the mark producing or character producing medium, it has been customary to use erasers composed or felt or the like for cleaning the slate, that is for removing the marks formed on the slate by the crayons aforesaid. When such felt erasers are used, it has been found necessary, as frequently as once a day, to use water or the like for washing the slate, otherwise the slate would shortly become so light in hue, that it would be difficult at the ordinarily required distance to distinguish the white crayon marks formed thereon. Slate, however, is porous and it has been found that while this water washing serves one purpose, the water actually helps to impregnate the pores of the slate with the chalk particles so that in time the pores will become so saturated with the resulting chalk paste that not only will the color of the slate be changed to a lighter shade and the legibility materially impaired, if not entirely destroyed, but in addition, the surface of the slate will be so changed in texture that it will not properly allow the chalk particles to form the intended mark or character, some of the chalk particles merely adhering to the spongy chalk paste in the pores and thereby discolored and others being discolored by the moisture of the chalk paste retained in such pores.

In view of the foregoing, it is an object of the present invention to provide an improved black board eraser which will effectively clean the slate of all chalk marks so that water or the like will not be required from time to time to remove the excess chalk particles which heretofore have remained on the slate when an ordinary felt eraser was used.

It is still another object of the present invention to provide an improved black board eraser which will not only obliterate the chalk marks or characters formed on the slate, but in addition, effectively remove all

excess chalk particles to prevent accumulation of the same in the pores of the slate and actually serve to polish the board.

It is still another object of the present invention to provide an improved black board eraser for effectively cleaning a black board of all chalk particles formed on the surface as well as those lodged in the pores of the slate and which erasers can be expeditiously cleaned.

It is still another object of the present invention to provide an improved black board eraser from which the chalk particles can be quickly and effectively liberated in the act of cleaning such erasers. To this end, the present invention more specifically aims to provide a black board eraser composed of felt and steel wool.

These and other features, capabilities and advantages of the invention will appear from the subjoined detail description of specific embodiments thereof illustrated in the accompanying drawings in which:

Figure 1 is a perspective looking at the bottom of one form of eraser;

Fig. 2 is a transverse section of the eraser illustrated in Fig. 1; and

Fig. 3 is an enlarged transverse section in perspective of another form of eraser looking at the top.

In the embodiment illustrated in Figs. 1 and 2 there is provided a black board eraser made according to the present invention having a base or supporting sheet 1, composed of felt or the like and two side sheets 2 and 3, also composed of felt or the like. The side sheets or walls 2 and 3 serve to protect the fingers of the user when using the eraser. These walls 2 and 3 may be secured to the base 1 by any suitable means such as the fibre threads 4 and 5 respectively.

Between the walls 2 and 3 in the embodiment illustrated in Figs. 1 and 2, there are provided a plurality of sheets of felt 6 which extend from the lower face 7 of the base 1 to the outer ends of the wall sections 2 and 3. These sheets 6 are similarly secured to the base 1 by any suitable means such for instance as the fibre threads 8.

Adjacent to the sections 6, there are pro-

vided a plurality of sheets 9 composed of steel wool.

In the act of erasing a black board with these erasers, the steel wool sections 9 will not only aid the felt sections 6 to remove the chalk particles but in addition thereto act as an abrasive, and penetrate the pores of the slate to liberate the chalk particles lodged in such pores. Due to its abrasive action, the erasers can also be used so that the steel wool will serve to polish the surface of the black board and thus not only remove the chalk marks but also obliterate any surface digs or scratches that might be formed in the slate by the crayon. Due to the natural resiliency of the steel wool fibre not only the felt sections 6, but also the steel wool sections 9 will be quickly freed of the chalk particles in the act of cleaning. These steel wool sections 9 are also secured to the base 1. In the present instance, they are shown as secured by the fibre threads 10.

In the embodiment illustrated in Fig. 3, the eraser there illustrated is provided with a base 11, similar to the base 1 of the aforesaid embodiment, and also preferably composed of felt. To this base 11, there are secured the side walls 12 and 13, also composed of felt, similar to the side walls 2 and 3 of the aforesaid embodiment. Between the side walls 12 and 13 in the present embodiment there is provided a rectangular block 14 composed of felt and steel wool fibre. This block 14 may be secured to the base 11 or to the walls 12 and 13 by any sort of suitable means.

In the present instance, the fibre threads 15 are provided to extend through the base 11 into the block 14. The felt particles of the block 14 serve not only as the binder for the steel wool fibres but also as a yieldable safety device, similar in action to the action of a cushion. In this way in the act of erasing, the steel wool particles will be prevented from freely rubbing against one another and thus abrading one another without performing any useful work. Furthermore, since the steel wool fibre is, of course, more compressible than the felt particles, the felt particles will serve as the support to bear the brunt of the erasing pressure and the steel wool particles will be free to act as a brush, its fine wire threads piercing the smallest portions to dislodge the chalk particles that might be retained therein.

The felt sections 6 of the embodiment illustrated in Figs. 1 and 2, will of course similarly serve to bear the brunt of the pressure exercised during the erasing action and similarly permit the steel wool sections 9 freely to act as a brush and not as a scratching surface.

The block 14 may of course be used as a black board eraser without the base 11 and side walls 12 and 13.

It is obvious that various changes and mod-

ifications may be made to the details of construction without departing from the general spirit of the invention as set forth in the appended claim.

I claim:

A black board eraser having a base composed of felt, felt finger protecting walls extending at right angles from said base, alternate sections of felt and steel wool extending at right angles from said base between said finger protecting walls with the exposed ends thereof terminating in a face parallel with said base, and means securing said finger protecting walls and sections of felt and steel wool to said base, the felt sections being less compressible than the steel wool sections to act as a guard for the surface being erased.
